UNITED STATES PATENT OFFICE.

LEWIS A. BROWN AND ROBERT LANG, OF ST. LOUIS, MISSOURI; SAID LANG ASSIGNOR TO SAID BROWN.

BRICK-MACHINE.

No. 828,377.

Specification of Letters Patent.

Patented Aug. 14, 1906.

Application filed February 26, 1906. Serial No. 302,946.

To all whom it may concern:

Be it known that we, LEWIS A. BROWN and ROBERT LANG, citizens of the United States, residing at St. Louis, Missouri, have invented 5 a new and useful Brick-Machine, of which the following is a specification.

This invention relates to brick-machines; and the object is to produce a machine consisting of a frame or support, compression devices carried thereby; and suitable adjustable formers or molds controlled by the compression devices.

In the drawings, wherein the preferred form of the invention is illustrated, Figure 1 is a plan view of the machine. Fig. 2 is an end view. Fig. 3 is a cross-sectional view. Fig. 4 is a bottom view. Fig. 5 is a sectional view taken approximately on the line 5-5 of Fig. 1. Fig. 6 is a perspective view of one of the formers or molds. Fig. 7 is a perspective view of a brick or block formed in the machine.

Referring specifically to the various parts, 1 indicates a frame or support having a plurality of pairs of slots 2, the two slots comprising each pair being alined, as shown in Figs. 1 and 4. Bearings 3 are provided on the under side of the frame or support 1, and shafts 4 are journaled in said bearings. Right 20 and left hand threads 5 are formed on said shafts. A bar 6 is provided across each series of the slots 2, said bars having threaded bearings 7, whereby they will be moved toward each other when the shafts 4 are turned, 25 as hereinafter described. Projections 8, rigid with said bars 6, project through the slots 2, as shown in Fig. 5, and the projections on the different bars likewise move toward each other when the shafts 4 are turned, 30 40 turned. A pinion 9 is attached to each shaft 4, and a gear 10, mounted upon a suitably-supported trunnion intermediate of said pinions, meshes with both of said pinions. A handle 11 affords means for turning said gear 45 10, and thereby the shafts 4.

For each machine there is provided a series of mold, or former supports 12, adapted to rest separately upon the frame or support 1, as shown. Said supports 12 are provided 50 with slots which when properly positioned register with the slots 2 and through which the projections 8 extend. Near one end of the support 1 is a rigid shoulder or brace 13,

which serves as an abutment for the support 12 and similarly as a guide for the formers or molds. Near the opposite end of the said support 1 is a bearing 14, which supports a screw-bolt 15. Said screw-bolt is pivotally connected at its inner end to a compression-plate 16.

The molds or formers are separate box-like structures removably located upon the former-supports 12 when in use. For shaping small blocks or bricks one pair of the projections 8 for each mold is sufficient; but 65 when large objects are to be shaped and a larger mold is utilized a greater number of the said projections are necessary properly to compress the mold and hold it in proper position. In all cases all the projections 8 on 70 each bar 6 are held perfectly alined, so that absolute regularity as to size is assured. In the form shown there are several molds on the machine, and each mold consists of two angular plates 17, arranged to form an open-top box, as clearly shown in Fig. 1, the side 75 of each plate bearing against the end of the laterally-bent portion of its associate. These box-like molds are arranged between the member 13 and the compression-plate 16. By 80 turning the screw-bolt 15 the molds will be pressed closely together and so held.

In using the machine the shafts 4 are turned to move the projections 8 toward the outer extremities of the slots 2. Upon a previously-positioned support 12 the molds are then adjusted between the two rows of projections 8. Within each mold a plate 18 is placed, said plates being of the same width as the molds and of uniform length. These plates prevent the plastic material that is poured into the molds from passing through the slots 2. After the plates 18 have been positioned the shafts 4 are turned to move the rows of projections 8 toward each other, and thereby 95 move the mold members 17 until they are stopped by the plates 18. Then the plastic material is poured into the molds, after which the mold-support 12 and the molds may be removed from the part 1 and another mold-support and another set of molds may be placed thereon.

In some instances it may be desired to form blocks or bricks with an adhering plate. This form of block or brick is shown in Fig. 7, 105 wherein the plate 19 adheres to the block 20,

said plate also being shown in position in an empty mold in Figs. 3 and 5. The plates 19 in such instances are provided with angular edges 21, which project upward at about 5 forty-five degrees when the plates are placed in the molds. Then when the plastic material is poured into the molds said edges 21 become embedded therein and rigidly adhere to the finished block or brick. The operation of 10 the machine is the same in all instances.

By this machine blocks or bricks of various sizes may be made, though at each operation only one dimension can be molded. There 15 may be variations within limits without departing from the spirit and scope of the invention, and we do not desire to restrict ourselves to inessential details; but

What we desire to secure by Letters Patent is—

- 20 1. A brick-machine comprising a series of molds, shafts, projections on the shafts, and means for rotating the shafts to move the projections and parts of the molds and thereby diminish the size of the molds.
- 25 2. A brick-machine comprising a series of molds, a support therefor, projections adjacent to said molds, a handle, and mechanism controlled by the handle to move the projections and diminish the size of the molds.
- 30 3. In a brick-machine, a mold comprising two angular members forming an open-box structure, and manually-operable mechanism for moving both of said angular mem-

bers and thereby to diminish the dimensions of the mold.

35

4. In a brick-machine, a support, a mold comprising two angular members, a plate removably positioned between said angular members, manually-operable devices for compressing the angular members together 40 laterally, and manually-operable mechanism for moving said angular members endwise.

5. In a brick-machine, a mold comprising two angular members, a plate removably positioned between said angular members, a 45 manually-operable device for moving said angular members laterally to compress them together, and manually-operable mechanism for moving said angular members endwise.

6. In a brick-machine, a mold comprising 50 two angular members, a plate between said angular members, a compression-plate at the side of one of said angular members, a manually-operable device for moving the compression-plate to bind the angular members together, and manually-operable mechanism for moving both of said angular members endwise, substantially as described.

In testimony whereof we hereto affix our signatures in the presence of two witnesses. 60
